RAZOR

Oliver J. Haynes, Piqua, Ohio, assignor to Townsend F. Beaman, Jackson, Mich., as trustee

Application April 3, 1952, Serial No. 280,329

1 Claim. (Cl. 30—53)

The present invention relates to improvements in safety razor having a flexible removable blade of the Gillette type.

In the above defined type of razor it has been the practice to clamp the blade into a slightly arcuate form with the handle of the razor extending from the concave side of the blade in its clamped position. With this type of construction, in shaving the face or beneath the arms the razor is manipulated in a manner comparable to a conventional garden hoe. While razors of this construction have been extensively used for many years, they are awkward to use especially when shaving beneath the arms or when shaving upwardly beneath the chin of the face.

According to the present invention, I have provided a safety razor which is similar in design and handling to a straight razor. The handle is angularly off-set from the head of the razor and is located on what might be termed the convex side of the blade when clamped in the razor head.

Thus, an object of the invention is to provide a razor of the type described in which the handle is angularly off-set from the head of the razor and extends from the convex side of the blade in its clamped position.

Another object is to provide an improved razor of the type described in which the head of the razor has a base portion integral with the handle and a hinge guard for supporting the blade with an arcuate form against the base.

Another object is to provide a safety razor having a head with a base portion having an integral guide and gauge rib for locating the blade as well as the adjustable guard.

These and other objects and advantages residing in the combination, construction and arrangement of parts will more fully appear from a consideration of the following specification and the appended claim.

In the drawings wherein one form of razor is illustrated embodying the principles of the present invention,

Fig. I is a side-elevational view with the guard shown raised in dotted outline,

Fig. II is a plan-view of Fig. I with the guard raised and the blade indicated in dotted outline,

Fig. III is a cross-sectional view taken on line III—III of Fig. I,

2

Fig. IV is an end view of Fig. I taken from the right side, and

Fig. V is an end view of Fig. I taken from the left side with the guard shown raised.

5 In the drawings, the illustrated form of the invention comprises a razor 10 having a head 12 and a handle 14. The head 12 comprises a base portion 16, preferably integral with the handle 14, and a guard 18 hinged to the base 16 by a pin 20. Both the base 16 and guard 18 are similarly arcuate with respect to their opposed surfaces to impart the desired arcuate form to the conventional double edge flexible razor blade indicated at 22.

10 As more clearly shown in Fig. V, the guard 18 has a slot 24 to receive and be guided into position by the guide and gauge rib 26. In using the razor 10, the longitudinal edge 28 engages the skin and determines the angle of the head as it rests on or is moved over the skin. Also, the rib 26 acts as a fulcrum about which the head 12 is rocked during shaving to bring either edge 20 of the double edged razor blade 22 into operation, depending upon the direction of the shaving stroke. To firmly hold the blade 22 in position, the guard 18 has a suitable latch 30 which engages around the end of the base portion 16 with spring tension to firmly hold the 25 guard with respect to the base portion 16 and to impart to the blade the arcuate shape of the opposed arcuate surfaces of the base 16 and guard 18.

20 It will be noted that the handle 14 is angularly off-set with reference to the head 12. Also the handle 14 is 30 located on the convex side of the razor with respect to the arcuate form of the blade in lieu of extending as a stem from the concave side as has been the standard practice with safety razors of the Gillette type.

Having thus described my invention what I claim as 35 new and novel and wish to protect by Letters Patent is: A safety razor comprising a head having a pair of parts with opposed surfaces shaped to clamp a flexible blade in an arcuate form, a removable flexible blade clamped between said parts, one of said parts being hinged 40 at one end and having a longitudinally extending centrally located slot, and the other of said parts having a handle at one end to which said first part is hinged and a guide and gauge rib on said second part to receive the blade and projecting through said slot in said first part 45 into an exposed position for contact with the skin.
